UNITED STATES PATENT OFFICE.

FRITZ A. ANDERSON, OF MILTON, WISCONSIN, ASSIGNOR, BY MESNE ASSIGNMENTS, TO THE BURDICK CORPORATION, OF MILTON, WISCONSIN, A CORPORATION OF DELAWARE.

ELECTRICAL CONNECTER.

Application filed December 22, 1921. Serial No. 524,089.

This invention relates to electrical connectors.

It will be explained as applied to a water cooled therapeutic lamp such, for example, as of the type disclosed in my U. S. Patent No. 1,435,193; granted November 14, 1922.

One of the objects of this invention is to provide an improved electrical connector.

Another object is to provide a connector which effectively assists in resiliently supporting the lamp.

Other objects are to provide a support connector which is simple in construction, inexpensive to manufacture, readily applied and used and reliable in operation.

Other objects and advantages will hereinafter appear.

An embodiment of the invention is illustrated in the accompanying drawing, 20 wherein

Fig. 1 is a side elevation of a part of a lamp, the enclosing housing being in section to expose the lamp tube and its improved connector.

Fig. 2 is a bottom plan of the lamp with the bottom of the housing removed.

Fig. 3 is a plan of the connector.

Fig. 4 is a side elevation thereof.

Fig. 5 is a plan of the blank from which 30 the connector is formed, and

Fig. 6 is an enlarged section of the clamping nut of the support.

The therapeutic lamp with which this supporting connector is particularly adapted for use comprises in general a lamp tube or burner 1 and an enclosing housing 2 within and by which the tube is carried. The tube is insertable into and removable from its position through an end of the

housing which may be closed by a removable bottom 3. Inasmuch as the tubes and housings are well known, one common type being illustrated in the patent heretofore mentioned, a showing of the lower end 5 thereof where the connector is applied will be sufficient for an explanation of my improved connector. Ordinarily the lamp tubes or burners have a cathode 4 within the tube which is electrically connected to an external terminal 4', commonly in the form of a metallic band about the tube adjacent its cathode end. Lateral bracing of the tube is provided by a number of resilient fingers 5 suitably secured to the housing.

Tube 1 is supported and connection is made to its cathode connector band 4' by a combined support and terminal. This support and connector has an expandable and contractible split clamping ring 6 which surrounds and closely embraces the terminal band 4' of tube 1. Ring 6 has a pair of mounting lugs 7 and 8 projecting outwardly and parallel from opposite edges thereof. The free ends 9 and 10 of ring 6 are bent so as to assume a substantially parallel relation and are provided with corresponding holes for a bolt 11. Lugs 7 and 8 are provided with elongated holes 11 and 12, respectively. A slit 13, extends between 70 hole 13 and the edge of lug 8.

Clamping ring 6 may be formed from a single punching of sheet metal such as shown in Fig. 5. The blank and the openings therethrough may be formed in one 75 operation. Bending the blank in the region of the dotted lines of Fig. 5 serves to give the clamp its finished structure as shown in Fig. 3 and 4.

A clamping nut 14 serves to hold the connector in place. The central zone of nut 14 is of reduced diameter to form a pair of heads 15 and 16. The forward end of the bore of nut 14 is enlarged and the rest of the bore is threaded. Clamping ring 6 and nut 14 are assembled together by opening the hole 12 at the slit 13 and positioning the reduced intermediate section of the nut within hole 12 of lug 8. This assembly may be accomplished by opening up slit 13 90 far enough to receive the nut. When the slit is again substantially closed nut 14 is loosely retained by the clamping ring.

Nut 14 is adapted to be screwed upon the projecting end of a threaded stud 17. Stud 95 17 is electrically connected to one of the lamp electric terminals and is firmly held in position on a suitable support in the housing by a nut 18. The enlarged part of the bore of nut 14 assists in the ready positioning of the nut on stud 17. When the nut is turned home on stud 17 the electrical connection to the cathode is made and the lamp is supported at least in part by the connector. The resiliency of lugs 7 and 8 renders the support shock absorbent and assists in protecting the lamp against breakage. The elongated holes in lugs 7 and 8, allowing some variation in the relative positions of the lamp tube and stud 17, facilitate the 110

installation of the tube within its housing.

Since the clamping ring and nut of the supporting connector are assembled as a unit the danger of losing the nut or misplacing it when a lamp tube is being changed is reduced. The proper positioning of the connector in the lamp housing is also made much easier as the nut is always approximately in place when a lamp tube is inserted.

10. To use the connector, the two parts of ring 6 are separated and the proper end of tube 1 is inserted therebetween. The ends 9 and 10 of the ring are brought together and secured by bolt 11 so that the band 4' or other terminal of the lamp tube is clamped by the ring. The tube and its connector are then inserted into the housing and nut 14 is turned upon stud 17. The elongated holes in lugs 7 and 8, the enlarged end of the bore 20 of the nut and the fact that the nut is approximately positioned when the tube is inserted all contribute to the easy and rapid placement and connection of the lamp.

Having described my invention what I claim as new and desire to secure by Letters Patent, is:—

1. A connector for a lamp which has a tube with an electrode therein and an external terminal connected to the electrode, comprising a split ring for embracing the lamp tube and engaging its terminal, means for clamping the ring about the tube, a pair of resilient outwardly extending lugs formed integral with said ring, said lugs being longitudinally slotted, and a nut held by one of said lugs so as to be capable of rotative and limited axial movement, and adapted to

secure the other lug to a current conducting support.

2. A connector for a lamp which has a tube with an electrode therein and an external terminal connected to the electrode, comprising a conducting and supporting ring for embracing the lamp tube and engaging the terminal thereof, a pair of resilient extensions on said ring, and a rotatable nut freely carried by one of said extensions for clamping the other of said extensions to a threaded support.

3. A lamp support and electrical connector comprising a ring for embracing the lamp tube and its external terminal, a pair of perforated lugs projecting from the ring, and a nut loosely and rotatably retained in the perforation of one of said lugs for attaching the other of said lugs to a threaded support.

4. An electrical connector for a lamp tube equipped with an external terminal, comprising a clamping ring for encircling the tube and electrically engaging the terminal thereof, a pair of spaced apart lugs projecting outwardly from opposite edges of the ring and having registering holes therethrough, and a nut having a restricted portion intermediate its ends and enlarged heads adjacent each end, the restricted portion being loosely positioned within the hole of one of the lugs and removal therefrom being prevented by the heads, said nut being internally threaded to attach the ring to a current conducting support.

In testimony whereof I hereunto subscribed my name.

FRITZ A. ANDERSON.
